JOHN AUSTIN BEST, INVENTOR

BY John A. Best,
ATTORNEYS

UNITED STATES PATENT OFFICE.

JOHN AUSTIN BEST, OF AUGUSTA, GEORGIA.

VISIBLE AND EXPANSIBLE CARD-INDEX.

Specification of Letters Patent. Patented Apr. 15, 1919.

1,300,334.

Application filed February 16, 1918. Serial No. 217,720.

To all whom it may concern:

Be it known that I, JOHN AUSTIN BEST, a citizen of the United States, residing at Augusta, in the county of Richmond and State of Georgia, have invented certain new and useful Improvements in Visible and Expansible Card-Indexes, of which the following is a specification.

My invention has relation to visible and 10 expansible card indexes.

The main object of the invention is to provide various means to enable one to expose to view or make visible names or other indicia contained on the index cards of card 15 indexes.

A further object of the invention is to provide means to accomplish the above without consuming any additional space than that now utilized by the common types of card 20 index systems now on the market.

A further object of the device is to provide means to carry out the above objects in a simple, expeditious, efficient and effective manner.

25 A still further object of my invention is to produce a device of the character above indicated, which may be termed a self-indexing card system.

With the foregoing and other objects in 30 view my invention consists of the novel features of construction, combination and arrangement of the several parts of my invention, which are described in this specification, illustrated in the accompanying drawing, 35 forming a part thereof and particularly pointed out in the appended claims.

Generally speaking, my present invention relates to a card having, at one edge at 40 least, a space, groove, channel, or the like, to receive a portion of the same edge of an adjacent card in a series in order that by pressure upon the series of cards at the said edges, movement of the opposite edges away from one another will be caused. Thus the 45 latter edges shifted away from one another will be placed in position where the indicia, as for instance the names, will be simultaneously exposed to view. My present invention contemplates for the above purpose,

50 a card having an extension along one or more edges projecting beyond the main body portion of the card, and which may be either reduced or offset with respect to the card body, although the reduced extension is to 55 be preferred as it avoids additional parts and attachments.

In the accompanying drawings illustrating my present invention:

Figure 1 is a face view of one form of 60 card embodying the invention;

Fig. 2 is an edge view thereof;

Fig. 3 is a face view of another form illustrating the extension in the nature of an attached part;

Fig. 4 is an edge view of a series of cards, 65 each constructed as in Fig. 3, placed to illustrate the practical use thereof;

Fig. 5 is a face view of another form of the invention;

Fig. 6 is an edge view of the card shown 70 in Fig. 5 and other cards similar thereto;

Fig. 7 is a face view of still another modified form of card, and,

Fig. 8 is an edge view showing a series of 75 the cards of Fig. 7 in the position illustrating their practical use.

In Figs. 1 and 2 I have shown a card 10 embodying my invention by virtue of its formation from a strip of material folded upon itself to form the main body of the 80 card, which it will be noted from Fig. 2 is of substantially uniform thickness, the extension of the card in this case being constituted by one free edge of one fold which projects beyond the adjacent edge of the 85 other fold, as seen at 11. It is obvious this extension 11 may be duplicated at all edges of the particular form of the invention under consideration, except the folded edge.

In Figs. 3 and 4 I have shown that the 90 same result may be accomplished by an additional strip 12 pasted or otherwise fastened securely along at least one edge of the card 13 to project therebeyond and uniformly for the full length of the said edge, 95 thus constituting an offset extension, enabling the desired action to take place in use as will be observed from consideration of Fig. 4.

In Fig. 5 I have shown a card 14 which, 100 as will be observed by reference to the first card of Fig. 6, is made up of two layers 15 and 16, the bodies of which are offset with respect to one another, so as to produce extensions 17 and 18 at the opposite edges 105 thereof, the cards being thus reversible.

By reference to the card 19 of Fig. 6, however, it will be noted that the two layers need only be offset at one edge to produce the desired result, and by reference to the 110 card 20 of Fig. 6 it will be noted that the body need not be in two layers, but may be

made of a single ply reduced in thickness along one edge to produce an extension 21.

In Figs. 7 and 8 I have shown a three ply card, the central layer or ply 22 of which is extended beyond the edges of the two side layers or plies 23 to produce extensions 24, the card so constructed being reversible and being capable of the desired action in a horizontal, as well as a vertical direction.

10 It is obvious from a consideration of the foregoing that all of the forms illustrated and described, provide an extension along at least one edge, so placed as to form a space along one edge of the body portion of the card, capable of receiving a portion of the adjacent card at one side thereof, in a series of cards, so that the pressure upon the series of cards at the said edges will cause movement of the opposite edges away from one another, and into position, where the indicia of the several cards will be simultaneously exposed to view.

I claim:

1. A card index consisting of a plurality

of cards, each of which has means along 25 one edge thereof to form a space adjacent and along said edge arranged to receive a portion of the next adjacent card at one side thereof, for the purpose described.

2. A card index consisting of a plurality 30 of cards, each having an extension along at least one edge of the body thereof forming a space along the said edge of the body arranged to receive a portion of the next adjacent card at one side thereof.

3. A card index consisting of a plurality 35 of cards, each having a reduced extension along at least one edge of its body, forming a space therealong arranged to receive a portion of the next adjacent card at one side 40 thereof.

In testimony whereof I affix my signature in the presence of two witnesses.

JOHN AUSTIN BEST.
